UNITED STATES PATENT OFFICE.

FRANK P. MOGRIDGE, OF MERTZTOWN, PENNSYLVANIA.

RUG AND CARPET.

1,119,856.

Specification of Letters Patent.

Patented Dec. 8, 1914.

Application filed April 27, 1914. Serial No. 834,783.

To all whom it may concern:

Be it known that I, FRANK P. MOGRIDGE, a citizen of the United States, and a resident of Mertztown, in the county of Berks 5 and State of Pennsylvania, have invented new and useful Improvements in Rugs and Carpets, of which the following is a specification.

My invention relates to rugs and carpets, 10 and pertains more particularly to two-faced chenille rugs.

The object of my invention is to produce a rug of greater weight and durability, and which will lie flat and cling to the floor and 15 which will not readily slide and fold up at its edges.

A further object thereof is to produce a rug or carpet of said character having a greater elasticity, and in which a mottled 20 color effect may be attained.

To these ends and others to be hereinafter set forth, my invention includes the combination and arrangement of component parts to be hereinafter described, and more 25 particularly pointed out in the claims.

In the accompanying drawings in which like reference characters indicate similar parts, Figure 1 is a perspective view of the rug of my invention; Fig. 2 is a similar 30 view showing the warp and filling slightly spread apart; Fig. 3 is a longitudinal sectional view thereof, and Fig. 4 is a transverse sectional view of the same.

As rugs of this character have been heretofore constructed, they comprised a warp of preferred thread, and a cross woof or filling of chenille of single strands. Rugs of such construction are liable, as shown by use, to turn up at their edges, and fail 40 to lie flat on the floor. To overcome this objection, and for the purpose of imparting a greater degree of elasticity and greater durability, and for the further purpose of accomplishing a mottled color effect, I have 45 doubled the cross strand or woof of chenille and twisted same in the weaving.

Referring to the drawings, 1 indicates the stuffer warp threads, and 2 designates the woof or filler threads, which, as shown, are woven on both faces of the warp by the 50 binder warp-threads 3; thus producing a double faced reversible carpet fabric. As shown in the drawings and for the purposes stated the woof threads 2 are doubled, and twisted on each other. 55

In the particular embodiment of my invention, the woof threads are preferably of chenille, and each of the pair may be of a different color or shade to impart a mottled effect to the rug, and said threads become 60 twisted, as they are unwound from the cop in weaving.

It will be appreciated that the structure thus described will impart a greater thickness and resiliency than would be had from 65 a single strand of woof threads of the same weight as both of the double strands, and that a mottled color effect may be attained in the rug by combining strands of woof in pairs of different colors or shades. 70

Having thus described my invention, what I claim as new, and desire to be secured by Letters Patent is—

1. A rug or carpet, comprising warp threads, and woof threads of chenille woven 75 therewith in units of two or more strands twisted on each other, substantially as described.

2. A rug or carpet, comprising stuffer warp threads, filled woof threads of chenille 80 in units of two or more strands twisted on each other woven on both faces of the warp threads, and binder warp threads interwoven with said twisted filler woof on the opposite faces of the stuffer warp, for the 85 purposes set forth.

FRANK P. MOGRIDGE.

Corrections in Letters Patent No. 1,119,856.

It is hereby certified that in Letters Patent No. 1,119,856, granted December 8, 1914, upon the application of Frank P. Mogridge, of Mertztown, Pennsylvania, for an improvement in "Rugs and Carpets," errors appear requiring correction as follows: Line 80, of the printed specification, for the word "filled" read *filler*; in the drawings the binder warp threads should be indicated by the reference-numeral 3; and that the said Letters Patent should be read with these corrections therein that the same may conform to the record of the case in the Patent Office.

Signed and sealed this 26th day of January, A. D., 1915.

[SEAL.]

R. F. WHITEHEAD,

Acting Commissioner of Patents.
